UNITED STATES PATENT OFFICE.

WILLIAM J. STOWELL, OF BALTIMORE, MARYLAND.

IMPROVED RAILWAY-SWITCH.

Specification forming part of Letters Patent No. 81,029, dated August 11, 1868.

To all whom it may concern:

Be it known that I, WILLIAM J. STOWELL, of Baltimore city, in the county of Baltimore and State of Maryland, have invented a new and Improved Railway-Switch; and I do hereby declare that the following is a full, clear, and exact description thereof, reference being had to the accompanying drawings, making a part of this specification, in which—

Figure 1 is a plan view of the improved switch applied to the main track-rails at a turn-out or siding. Fig. 2 is a perspective view of the same.

Similar letters of reference indicate corresponding parts in the two figures.

This invention relates to railroad-switches which are applied at the junctions of turn-outs with main tracks, for the purpose of allowing trains to leave a main track and pass off upon a siding, and also to pass from a siding upon a main track.

The nature of my invention and improvement in switches consists in connecting a laterally-movable rail-section of one side of the turn-out with a laterally-movable rail-section of one side of the main track, and in connecting the laterally-movable inside rail-section of the opposite side of the turn-out with said movable main track and turn-out rail-sections, by means of levers and rods, in such manner that the three sections will all move together, and may be adjusted and set for the main track or turn-out at pleasure, said parts being so constructed and connected together that, should the switch be improperly adjusted for a train running upon the main track, no accident is liable to occur, all as will be hereinafter explained.

The invention further consists in providing the switch-lever by which the switch-rails are adjusted with an auxiliary lever, which will assist in moving the switch, and employing a hook-fastening in conjunction therewith for retaining the switch-rails in position when they are set for the siding, as will be hereinafter described.

To enable others skilled in the art to understand my invention, I will describe its construction and operation.

In the accompanying drawings, A A represent the main-track rails, which are spiked down upon their cross-ties G G¹ G² G³ G⁴ in the usual well-known manner.

B B represent the fixed rail-sections of the siding or turn-out, which it is desired to connect with the main track at certain times by means of my improved switch.

Between the main track-rails A A, and jointed to the inside rail-section, B, by a shoe, a, or in any suitable manner, is a rail-section, B¹, which is held in a plane parallel, or nearly so, to the movable turn-out section B², as will be hereinafter described. This horizontally-vibrating section B¹ is tapered, as shown in Figs. 1 and 2, so that its sharp end shall not offer an obstruction to car-wheels passing from the main track upon it when it is adjusted, as shown in red lines, Fig. 1. In order to allow this tapering section B¹ to fit snugly against the lip of the main rail-section A when adjusted against it, as indicated in red, a portion of the rail-bases of the rails are cut away, as shown.

An offset, g', is secured in a suitable manner to the rail-section B¹, to which is pivoted a connecting-rod, g, which rod extends transversely across the main track, and is jointed to the short arm of a lever, f. This lever f is pivoted to an offset, e, projecting from the inside of a main-track-rail section, A¹, and also to the cross-tie G² at the point d. The rail-section A¹ is confined to a cross-tie, G⁴, by means of a saddle or lipped chair, C, and all that portion of this section A¹ which extends to the lipped chair b is allowed to spring laterally, so that the end which rests upon said chair b may be moved in a lateral direction a few inches by the natural spring of the metal of this rail-section.

Outside of the main-track rail A¹, and secured thereto or formed thereon, is a slightly-curved rail-section, B², which belongs to the siding, and which rests at one end upon the chair b, and at the other end upon the chair c, to which latter the end of this rail-section is secured firmly, as shown in Fig. 1.

The plates d d, which are secured upon the cross-ties beneath the two laterally-movable rail-sections A¹ B², are merely face-plates, to serve as bearings upon which said sections may be vibrated.

It will be seen from the above description that the rails B¹, A¹, and B² are connected together in such manner that they will vibrate together.

When the rail-section A¹ is in line with the

main-track rails A, as shown in black lines, Figs. 1 and 2, the two turn-out-switch sections B¹ B² will be located to one side of their respective main-track rails, and when the free end of rail-section B² is moved in line with its main-track rail A the free end of section B¹ will be brought up closely against the inner side of its main-track rail by the operation of the lever f and connecting-rod g, as shown in red lines, Fig. 1.

An offset, h, is secured to the free end of the switch-section B², and projects laterally from the outer side thereof, and to this offset a rod, i, is pivoted, which is pivoted again to the short arm of a switch-lever, D. This switch-lever D is pivoted to a standard, C, and passes up through an oblong slot made through the upper overhanging end of this standard, as clearly shown in Fig. 2. A lever, E, is pivoted to the overhanging portion of said standard, so as to vibrate in a horizontal plane and serve as a means for facilitating the drawing

back and holding of the lever D in the act of adjusting the switch for the turn out. The hook j, on one side of standard C, will serve to retain lever E in place while holding back the lever D, as indicated in red lines, Fig. 1.

Having described my invention, what I claim as new, and desire to secure by Letters Patent, is—

1. The combination of vibrating switch-rails B¹ B² of the siding with the vibrating switch-rail A¹, forming part of the main track, said rail-sections being arranged and connected together substantially as and for the purposes described.

2. The auxiliary lever E, with its fastening j applied to the standard C of the switch-lever D, substantially as and for the purposes described.

W. J. STOWELL.
